UNITED STATES PATENT OFFICE.

FREDERICK FARMER, OF WORCESTER, MASSACHUSETTS.

LINGO HEDDLE.

Application filed July 5, 1923. Serial No. 649,590.

To all whom it may concern:

Be it known that I, FREDERICK FARMER, a citizen of the United States, residing at Worcester, in the county of Worcester and 5 State of Massachusetts, have invented a new and useful Lingo Heddle, of which the following is a specification.

This invention relates to a lingo or lingo heddle. The principal objects of the invention are to improve the construction of the ordinary lingo or lingo heddle so that it will be more durable, more easily assembled and capable of ready detachment when the supporting cord is broken and prevent the 10 necessity of throwing away the connecting device that is usually discarded in the old constructions and especially to provide for more ease of attachment of the parts and facilitate the repair of the heddle.

Reference is to be had to the accompanying drawings, in which—

Fig. 1 is a front view of a lingo heddle constructed in accordance with this invention and shown in its complete condition;

Fig. 2 is a side view partly in section of the detachable connecting parts at the top shown separated;

Fig. 3 is an edge view of the heddle eye partly in section;

Fig. 4 is a side view of the bottom eye of the heddle;

Fig. 5 is a perspective view of the heddle wire before attachment to the heddle; and

Fig. 6 is a front view of the heddle eye with only one of the wires attached.

I have shown the invention as applied to a wire heddle having a central eye formed in a sheet metal plate 10. This plate is provided with two rectangular transverse perforations 11 preferably. Each of the two wires 12 which is to be attached to the heddle eye is provided with a long flattened portion 14 and bent at the center of this so as to double it over. The width of the flattened portion is the same as the width of the perforation 11. The same is true of the thickness. The wire is inserted through the perforation and the parts doubled over and brought into contact and soldered together on the piece of sheet metal 10.

This constitutes an important feature of the device. It permits of ready attachment of the parts and by melting the solder the wires can be withdrawn and very readily re-

placed or the eye replaced with comparatively little difficulty. Furthermore, the attachment of the wires through a non-circular perforation co-operating with the flattened portion 14 insures the anchoring of the wire in exactly proper position so that they cannot be accidentally put on at a slight angle to the proper location.

At the top of the heddle it is provided with the usual hook 15 for the reception of the loop cord 16 for supporting it. This is covered by a clip 17 made preferably of sheet metal of a cylindrical form and having a reduced end portion. Instead of relying upon the friction of the parts to hold this in position I provide a second fastening clip 20 above it made in the same way and of the same general form but larger in cross-section so that it will fit over the cylindrical end of the lower clip. It is also provided with a longitudinal slit 22 permitting of its 55 springing over this clip and on account of this I contract the open edge a little to cause it to hug tight on the contracted portion of the lower clip when in position. In this way friction of these parts holds the whole 60 fastening device together and at the same time when the cord breaks the two clips are readily separated from each other and are attached after replacement of the cord or the lingo. This eliminates the necessity of 65 throwing away the fastening device or the lingo heddle which has been a source of expense heretofore.

At the lower end the lower eye 25 is formed with a shank at its end running along the 70 wire a little way and this shank is turned up at 27 to form a hook which extends around the wire. This is manufactured in a straight form but when applied in position the operator presses on the end of the hook and 75 forces it down on the wire to make the joint permanent. This affords a ready and simple means of detaching one end of this eye from its wire.

Although I have illustrated and described 80 only a single form of the invention and shown the three features above mentioned applied to the same lingo heddle, I am aware of the fact that this invention can be applied 85 to other lingoes or lingo heddles as well, and that modifications can be made therein by any person skilled in the art without departing 90 from the scope of the invention as ex-

pressed in the claims. Therefore I do not wish to be limited to the details of construction herein shown and described or to the combination of each of these features with the others but what I do claim is:—

- 5 1. A lingo or lingo heddle having an eye piece, a wire supporting it having a hook at the top, a cord loop extending over the hook, a clip slideable on the wire for covering the hook and loop, and means on the cord for frictionally holding the clip.
- 10 2. As an article of manufacture, a lingo or lingo heddle having in its complete state an eye supported by a wire, the wire having a hook at the top for receiving the loop of a cord and having a clip slideable on the cord and capable of surrounding the top of the hook; and means for retaining the clip in position.
- 15 3. As an article of manufacture, a lingo heddle having a hook at the top for receiving the loop of a cord and having a clip extending over the hook and bottom of the loop to protect them and provided with a second clip slideable on the cord and capable of sur-
- 20 25

rounding the top of the first clip and holding it frictionally.

4. An article of manufacture, a lingo heddle having a hook at the top for receiving the loop of a cord and having a clip extending over the hook and bottom of the loop to protect them and provided with a second clip slideable on the cord and capable of surrounding the top of the first clip and holding it frictionally, the second clip having a cylindrical portion fitting the first clip and being narrowed at its open end and provided with a longitudinal slit to allow it to yield and to press on the lower clip with a spring pressure.

5. The combination with a lingo heddle having a hook at the top, a cord loop through the hook and a clip slideable on the wire of the heddle for covering the hook and loop with a second clip slideable on the cord and having means for frictionally holding the first named clip.

In testimony whereof I have hereunto affixed my signature.

FREDERICK FARMER.
